[57] CLAIM

The ornamental design for a two burner cooker, as shown and described.

DESCRIPTION

FIG. 1 is a front perspective view of a two burner cooker showing our new design;

FIG. 2 is a top plan view;

FIG. 3 is a front elevational view, the rear elevational view being the same;

FIG. 4 is an end elevational view, the other end elevational view being the same;

FIG. 5 is a bottom plan view;

FIG. 6 is a front perspective view of a second embodiment of the invention;

FIG. 7 is a front elevational view of the structure shown in FIG. 6; and,

FIG. 8 is an end elevational view thereof.
